THEODOR KROMER, OF FREIBURG, IN BREISGAU, GERMANY, ASSIGNOR TO THEODOR KROMER GESELLSCHAFT MIT BESCHRÄNKTER HAFTUNG, OF FREIBURG, IN BREISGAU, GERMANY

SAFETY LOCK

Application filed February 29, 1928, Serial No. 258,073, and in Germany June 3, 1927.

My invention relates to that class of locks which can be opened by means of a handle after setting up a secret combination of symbols. What I propose by my invention is to keep the lock spindle outside the operative reach of the members which allow the bolt to be shifted, until the combination of symbols has been set up and so to increase the security of the lock against unwarranted opening. This end is obtained by the means explained below with reference to the accompanying drawing. In the latter:

Fig. 1 represents a vertical section passing through the lock spindle;

Fig. 2, a view of the lock from behind, with cover plate removed;

Fig. 3, a similar view, the bolt being removed;

Fig. 4, a further view of the inside of the lock with the dividing wall omitted;

Fig. 5, a view of a detail;

Figs. 6 and 7 are two opposite views of a detail; and

Fig. 8, a cross-section of the same.

In the drawing, 1 denotes the rotatable, axially adjustable lock spindle which carries a handle 2 in the form of a knob. In an enlarged part 3 of the lock spindle, two pins 4, 5 are adjustably mounted on springs 6 in radial recesses. According to the axial position of the spindle 1, these pins come into engagement with locking discs 7, 8 or 8, 9, by engaging in notches in the setting discs 10 which, by being rotatably adjustable in the locking discs, are capable of effecting the change of the combination. With the teeth of each of the setting discs engage two follower pins 12, under the influence of springs 11, and produce the connection with the corresponding locking discs. The outermost setting discs 10 have eccentric inner edges 13 which terminate in shoulders 13a adapted, on a right-hand rotation of the spindle, to be engaged by pins 4 and 5 for setting the locking discs. The centre disc 10 has a notch in which one of the pins always engages, irrespective of the position of the spindle. By pressing in the lock spindle in the direction indicated by the arrow in Fig. 1, and by rotating the spindle to the

right, the locking disc 7 can be set by means of the pin 4 which engages the shoulder 13a of the corresponding setting disc while, when the spindle 1 is pulled back and again rotated to the right, the pin 5 effects the setting of the disc 9. When the locking discs 7, 9 have been thus set up, the disc 8 which, as previously stated, always remains in engagement with one of the pins, can be set by turning the spindle to the left so as not to disturb the setting of the discs 7 and 9. By turning the spindle 1 to the left the pins 4 or 5 cannot get in operative engagement with any of the shoulders 13a of the setting discs 10 and, sliding on the eccentric edges 13, the pins are forced into the radial recesses of spindle 1 against the action of the springs 6. The middle locking disc has a toothed periphery 14, with which engages a detent pin 15 which is under the influence of a spring and serves to secure the locking disc in the proper position when being set. The rounded end of the pins 4, 5 and the bevelled edges 16 of the axial bore of the setting discs 10, ensure an easy axial displacement of the spindle 1 and render any tampering with the combination difficult. A wall 17 dividing the lock casing has a recess 18 to carry a circular flange 19 of the setting disc that projects over locking disc 7. A locking lever 22 is mounted on a pivot 21, fitted in recesses in the lock bottom and cover and projecting through the gap 20 of partition wall 17. A flat spring 23 secured to the pivot 21, carries a locking member 24 which, together with spring 23, penetrates through the gap in the partition wall and drops into notches 25 in the locking discs after said notches have been aligned by the setting of the discs. The lever 22 has a nose 27 which normally bears against one of the bolt-guiding pins 26. It has also a circular opening 28 which, when the member 24 drops into the notches 25, and owing to the pendulous suspension of the locking lever, passes immediately in front of the spindle 1 and permits the flattened extremity 29 of the spindle to enter a correspondingly shaped opening in an eccentric 30 whereby the lock bolt 33 is operated.

A disc 31, which is secured to the spindle 1 and which moves within a recessed escutcheon 32 on the door, may carry the symbols with reference to which the different lock combinations are set up.

It is important that, on retracting the bolt 33 from the sheet position, the setting of the locking discs 7, 8, 9 should be disturbed. For this purpose the discs 7, 8, 9 are turned by rotating the spindle 1 to the right. Only after the discs 7, 8, 9 have been turned the spindle 1 is displaced axially so as to re-enter the eccentric 30 for withdrawing the bolt 33 from its shut position by a further turning of spindle 1. By the first said rotation of spindle 1 the locking member 24 is forced out of the notches 25. Hence it is impossible to find out the combination when the lock is open. The locking discs may be displaced, and the member 24 forced out of the notch 25 in spite of the lever 22 being held fast by the spindle 1, owing to the resilience of the spring 23.

The securing of the lock with the bolt 33 in shut position is effected, after pulling back the spindle 1, by turning the locking discs to the right so as to force the locking member 24 of the lever 22 out of the notches 25 whereby the lever 22 is moved to the opening 28, being displaced with reference to the spindle 1, the latter being prevented from engaging the bore of the eccentric 30.

I claim:

1. In a lock, the combination with a lock bolt and with an operating element for the same, of a rotatable lock spindle adapted to be axially displaced for engagement with and disengagement from said operating element, a pivoted blocking lever adapted to enter the passage between the spindle and said operating element, a plurality of discs mounted on the spindle, a resilient controlling arm on the lever resting on the discs and maintaining the lever normally in blocking position, the discs being provided with peripheral notches into which, when in alignment, the arm can drop so as to release the lever, and means on the spindle whereby the latter can be used for setting the discs in lever-releasing position.

2. A structure as claimed in claim 1, wherein the disc-setting means consist of spring-controlled pins mounted in the spindle and adapted to engage shoulders on the inner edges of the discs, said inner edges being bevelled so as to enable the pins to slip easily from one disc to another on an axial displacement of the spindle.

THEODOR KROMER.
